UNITED STATES PATENT OFFICE.

PETER I. WOLD, OF EAST ORANGE, NEW JERSEY, ASSIGNOR TO WESTERN ELECTRIC COMPANY, INCORPORATED, OF NEW YORK, N. Y., A CORPORATION OF NEW YORK.

METHOD AND MEANS FOR RELAYING MODULATED CARRIER WAVES.

1,424,866.

Specification of Letters Patent. Patented Aug. 8, 1922.

Application filed February 17, 1917. Serial No. 149,818.

To all whom it may concern:

Be it known that I, PETER I. WOLD, a citizen of the United States, residing at East Orange, in the county of Essex and State 5 of New Jersey, have invented certain new and useful Improvements in Methods and Means for Relaying Modulated Carrier Waves, of which the following is a full, clear, concise and exact description.

10 This invention relates to systems for relaying or repeating such signals or other low frequency impulses as are carried by high frequency oscillations of the type used in radio transmission.

15 In particular it embodies a system in which high frequency oscillations, modulated in accordance with low frequency signals, are received at an intermediate or relay station and are so changed in character 20 that there is no tendency to produce "singing." This object is attained by receiving, at the relay or repeating station, the modulated high frequency oscillations and impressing them on a suitable device, such as a 25 thermionic vacuum tube modulator. The output circuit of such a modulator will contain a certain number of oscillations of high and of low frequency, one at least of which consists of a carrier wave of double the original 30 carrier frequency and modulated in accordance with the original signal. This component of the output may be selected out by suitable circuits and, after amplification, may be transmitted to a remote station. This 35 modulated doubled frequency will have little or no effect upon the receiving antenna at the repeating station for the receiving system is tuned to the original carrier frequency. Thus the tendency to "sing" which 40 is so common in all relay systems is eliminated.

In British Patent 142,371, it is shown how singing at a wireless repeating station may be avoided by combining the modulated 45 waves received at a repeating station with locally generated oscillations of another high frequency, whereby modulated oscillations are produced having a carrier frequency different from the carrier frequency 50 received. Modulated oscillations of the new carrier frequency are transmitted from the repeating station to a distant station, the receiving apparatus at the repeating station being unresponsive to the new carrier frequency.

If the local generator at the repeating station does not keep in step with the generator at the sending station, beats will be produced having a frequency equal to the difference in the frequencies of the generators. 60 The beats are objectionable as they mask the signal to be received.

The present invention relates to improvements in the above system, in that the local generator at the repeating station is dispensed with and the carrier frequency is changed by impressing the received modulated wave upon an audion tube or a similar device having a curved input-voltage, output-current characteristic, and which functions as does a modulator to produce sum and difference frequencies. In the ordinary method of modulation, when the carrier frequency p is modulated by the low frequency a , there are produced the sum and difference frequencies $p+a$ and $p-a$, termed in the art, "side frequencies" which, with the carrier frequency p , go to make up the ordinary modulated wave. 70

According to the present invention, the three components, p , $p+a$, and $p-a$ are combined in a modulator to produce in a similar manner the sum frequencies $p+(p+a)=2p+a$, and $p+(p-a)=2p-a$, and $(p+a)+(p-a)=2p$. These three components 75 $2p$, $2p+a$, and $2p-a$ represent a carrier wave of frequency of $2p$, modulated by the low frequency a . These components may be selected from the various frequencies supplied by the modulator, amplified and transmitted 80 to a distant station, without affecting the local receiving apparatus which is responsive to the modulated carrier frequency p and not to the modulated carrier frequency $2p$. A local circulation of power or singing 85 at the repeating station is accordingly avoided.

In the figure, the message transmitted from the sending station X is received by the repeating station Y where it is repeated 100 at a new carrier frequency and transmitted to the receiving station Z .

The conventional representation of an audion in the drawing is the same regardless of whether it is used as an amplifier, a 105 modulator or a detector. To facilitate a reading of the drawing each audion is provided with an auxiliary reference letter which is the first letter in the word which indicates the function the audion performs, 110

for instance, A=amplifier, M=modulator, D=detector.

The sending station X comprises a source of carrier currents 1 which are modulated in any suitable manner by the signals impressed on the signaling device 2. As shown herein the signaling currents in the circuit 3 and the carrier currents from source 1 are impressed on the input circuit 4 of the vacuum tube modulator 5 of the audion type. The grid 22 of modulator 5 is maintained at a negative potential by battery 23 and space current in the modulator output circuit is supplied by battery 24. The carrier currents are variably amplified in accordance with the comparatively slowly varying potential which the signaling currents assign to the grid 22. This modulating system is described and claimed in United States Patent 1,350,752 to H. J. Van der Bijl, high frequency signaling, patented August 24, 1920.

The modulator M supplies a modulated wave of usual form having the components p , $p+a$, $p-a$. To improve the quality of the speech received at station Z, as later described in detail, one of the side frequencies $p+a$ or $p-a$ is suppressed, for instance, by means of the filter F of the well-known Campbell type, coupled to the output circuit of modulator M by means of the transformer 25. The unsuppressed components, having frequencies p and $p+a$ or p and $p-a$, depending upon whether $p-a$ or $p+a$ has been suppressed, may be amplified by means of one or more amplifiers 26 similar to amplifiers 15 at station Y. The unsuppressed components, after amplification, are sent to the antenna 7 by means of the transformer 6. The modulated wave having either the components p and $p+a$, or p and $p-a$, is transmitted from station X and received by the antenna 8 at receiving station Y. Coupled to the antenna 8 by means of the transformer 9 is the amplifier 10, the input circuit of which is tuned flatly to the mean of the frequencies to be received. The output circuit of the amplifier 10 and the input circuit of the modulator 11 are tuned by means of the condensers 12 and 13, respectively, to the modified modulated wave to be transmitted. The output circuit of the modulator 11, which is a vacuum tube of the audion type, is tuned by means of the condenser 14 to transmit the frequencies $2p$ and $2p+a$, currents of these frequencies being amplified by the bank of amplifiers 15, the input circuit of which is tuned by means of the condenser 16 to the frequencies $2p$ and $2p+a$, and the output circuit of which delivers the amplified components $2p$ and $2p+a$ to the antenna 17. Thus by combining the energy of the incoming modulated waves with energy of different characteristic, such for example as that supplied by the space cur-

rent sources of the vacuum tubes, modulated waves of a carrier frequency twice that of the incoming waves are produced. Modified modulated currents of the double carrier frequency are transmitted to the antenna 18 at the receiving station Z. Any suitable means may be provided at this station for receiving the signal. For instance, the received modulated wave may be detected by the detector 19 of the audion type, the input circuit of which is tuned to receive the frequencies $2p$ and $2p+a$ by means of the condenser 20, and in the output circuit of which is provided a telephone receiver 21.

The manner in which the quality of the speech received at station Z is improved by filtering out and suppressing one of the side frequencies $p+a$ or $p-a$ will now be explained. If station X transmits each of the components p , $p+a$, $p-a$, then currents of the following frequencies will be received in the output circuit of modulator 11, $2p$, $2p+a$, $2p-a$, $2p+2a$, $2p-2a$. The detector 19 acts as does the modulator 11 to produce the sum and difference frequencies, so that the above frequencies, when transmitted from station Y and received at station Z, where they are impressed on the input circuit of detector 19, produce in the output circuit of this detector the following high frequencies: $4p$, $4p+a$, $4p-2a$, $4p+3a$, $4p+4a$, which are inaudible, and the signal frequencies a , $2a$, $3a$, and $4a$. The frequencies $2a$, $3a$, $4a$ are overtones of the fundamental frequency a and the received signal wave form of frequency a will be distorted because of these overtones.

It is desirable to prevent the overtones from masking or distorting the receiving signal and to this end the invention provides, preferably at the sending station X, the filter F to suppress one of the side frequencies, either the frequency $p+a$ or $p-a$, so that there is transmitted from station X either the frequencies p and $p-a$, or p and $p+a$. In case a modulating system of the type shown is used at station X, then preferably the filter is located between the modulator 5 and the amplifiers 26 so that the amplifiers need handle only the frequencies to be radiated. It is obvious, however, that the filter F may be located anywhere in the sending and receiving system in advance of the modulator 11.

When the filter F is used and the modulator 11 is supplied with only the frequencies p , and $p+a$, for example, the output circuit of the modulator will contain the following frequencies: $2p$, $2p+a$, $2p+2a$. These frequencies on being received at station Z will produce in the output circuit of the detector 19 the following high frequencies: $4p$, $4p+a$, $4p+2a$, $4p+3a$, $4p+4a$, which are inaudible, and only the signal frequencies a and $2a$, and the amplitude of a as compared to that of $2a$

is found to be large. When both side frequencies are freely transmitted, as first assumed, the amplitude of frequency a as compared to that of $2a$ is less than when the 3 filter is used, while the amplitude of the component a as compared to the sum of the components $2a$, $3a$ and $4a$ is still less. The advantage of using the filter is apparent as the overtones $3a$ and $4a$ are practically 10 entirely suppressed, and the comparative amplitude of $2a$ to a is reduced.

In addition to the above described reduction in amplitude of the overtone $2a$, a further reduction may be secured by making 15 the amplitude of the frequency p large as compared to the amplitude of the side frequency transmitted, $p+a$ for example, as above assumed. This may be done by transmitting from the sending station, a large 20 amount of unmodulated carrier currents. If the amplitude of p is large as compared to that of $p+a$, then in the output circuit of modulator 11, the amplitude of $2p$ and $2p+a$ will be large as compared to the amplitude 25 of the frequency $2p+2a$ which is the first overtone of the weak fundamental frequency $p+a$. It follows that, in the output circuit of detector 19, the amplitude of the audible frequency a will be large as compared to that of $2a$, since the amplitude of a depends on the combination of the frequencies $2p$ and $2p+a$, both of which are strong, while the amplitude of the frequency $2a$ depends on the combination of $2p$ and 30 $2p+2a$, the latter $2p+2a$ being comparatively weak in amplitude.

As the modulated wave transmitted from the antenna 17 at the station Y has the carrier frequency $2p$, to which the antenna 8 40 at station Y is unresponsive, a local circulation of power or singing at the station Y is prevented.

While the invention has been described in connection with a radio telephonic signaling 45 system, it is obviously equally applicable to either wire or radio systems in which signals of any form, control impulses for distant mechanism, or other transmitted energy appears in one stage of transmission as varying or interrupted electrical current.

What is claimed is:

1. The method of repeating electrical impulses which consists in receiving from a distant station carrier waves modulated in 55 accordance with said electrical impulses, controlling local energy by said received waves to produce similarly modulated waves having a carrier frequency which is different from that of said received waves and which 60 is determined solely by the received waves and independently of any characteristic of said local energy, and transmitting said modulated different frequency carrier waves to a remote point.

2. The method of repeating electrical im-

pulses which consists in receiving from a distant station carrier waves modulated in accordance with said electrical impulses, controlling local energy by said received waves to produce similarly modulated waves having a carrier frequency which is different from that of said received waves and which is determined solely by the received waves and independently of any characteristic of said local energy, and amplifying and transmitting 70 said modulated different frequency carrier waves.

3. The method of transmission by means of carrier waves modulated in accordance with electrical impulses which consists in 80 transmitting substantially exclusively currents of the carrier frequency and currents of one side frequency.

4. The method which comprises producing a complex wave having components of 85 the carrier frequency p and the side frequencies $p+a$ and $p-a$ differing from the frequency p by the signal frequency a , and in suppressing one of said side frequency components.

5. In a repeating system, the combination of a high frequency line adapted to receive a signal modified carrier wave from a distant station, a local source of energy, means for controlling said local energy by said received wave to produce a resulting similarly modified carrier wave having a carrier frequency differing from that of the received wave and which is determined solely by said received wave independently of any characteristic of said local energy, and means for transmitting 90 said resulting different frequency carrier wave.

6. A repeating system comprising a high frequency line adapted to receive a signal 105 modified carrier wave from a distant station, means for deriving from said received carrier wave a second carrier wave similarly modified and having a carrier frequency which is a multiple of that of said received 110 wave and which is determined solely by said received wave independently of any local agency, and means for selecting said multiple frequency carrier wave for transmission.

7. A repeating system comprising a high 115 frequency line adapted to receive from a distant station a carrier wave modulated in accordance with signals, means for controlling local energy by said received wave to produce a second modulated wave having a 120 frequency twice that of said received wave and which is determined solely by said received wave independently of the characteristics of said local energy, means for selectively amplifying said second modulated 125 wave of doubled carrier frequency, and means for transmitting said modulated wave of doubled carrier frequency to a distant station.

8. The method of repeating signals which 130

comprises receiving carrier waves modulated in accordance with said signals and controlling by the energy of said modulated carrier waves energy of different characteristic to produce modulated waves having a carrier frequency twice that of said received modulated waves, and which carrier frequency is determined solely by said received carrier waves independently of any quality 10 of said energy of different characteristic.

9. The method of radio transmission which comprises causing the energy of received carrier waves modulated in accordance with impulses of lower frequency to 15 control energy from a local source to produce similarly modulated carrier waves having a carrier frequency twice that of said received modulated waves, and which carrier frequency is determined solely by said 20 received carrier waves independently of any characteristic of the energy of said local source.

10. The method which comprises modulating a carrier wave, suppressing one of the components of the modulated wave, and 25 distorting the wave form of the resulting energy by combining its components to produce a second carrier wave of different frequency modulated in the same manner as the first mentioned carrier wave.

11. A transmission system comprising means for producing a carrier wave, means for modulating said wave, means for suppressing one of the components of the modulated wave, and means for distorting the 35 wave form of the resulting energy by combining its components to produce a second carrier wave of different frequency modulated in the same manner as the first mentioned carrier wave.

In witness whereof, I hereunto subscribe my name this 16th day of February A. D., 1917.

PETER I. WOLD.
